UNITED STATES PATENT OFFICE.

GEORGE A. HUGHES, OF ATOKA, KENTUCKY.

STORM-APRON.

SPECIFICATION forming part of Letters Patent No. 757,749, dated April 19, 1904.

Application filed December 1, 1903. Serial No. 183,382. (No model.)

To all whom it may concern:

Be it known that I, GEORGE A. HUGHES, of Atoka, in the county of Boyle and State of Kentucky, have invented certain new and useful Improvements in Storm-Aprons; and I do hereby declare the following to be a full, clear, and exact description of the invention, such as will enable others skilled in the art to which it appertains to make and use the same.

This invention relates to certain new and useful improvements in storm-aprons for carriages and the like.

The invention has for its object the production of an apron of this character which may be readily and quickly placed in position to protect the occupants of a carriage or the like from rain, sleet, snow, &c.

A further object is to provide an apron of this character which will readily deflect moisture and guide the same away from the interior of the carriage.

A further object is to provide means for affording a maximum protection for the rein-openings, whip-socket, and the like.

In carrying out my invention I provide a hood adapted to fit over the dashboard of a vehicle, the free end of the apron being supported by suitable straps suspended from the top of the vehicle, said free end being reinforced and connected with the top of the hood by a central strap, whereby the middle part of the apron is supported in such manner that the sides will slope gradually away therefrom, forming a perfect water-shed.

The invention will be hereinafter fully set forth, and particularly pointed out in the claims.

In the accompanying drawings, Figure 1 is a view in perspective, illustrating my invention. Fig. 2 is a horizontal sectional view illustrating the connection between the hood and apron. Fig. 3 is a longitudinal sectional view. Fig. 4 is a detail view of the apron detached.

Referring to the drawings, 10 designates a hood formed of two members 11 12. The part 12 is folded upon itself and is provided with an inverted-V-shaped end portion 13, the piece 11 being of triangular shape, the sides or legs 5c of the triangle conforming to the shape of

the cut-out portion 13 of part 12, the meeting edges of these parts being united by stitches or other suitable fastening means.

The apron 14 is of any preferred width, the lower edge thereof being cut out in approximate V shape, as indicated at 15, the angle of this opening being greater than the angle of the cut-out portion 13 of the hood. The edges of this cut-out portion 15 of the apron are united between the meeting edges of the parts 11 and 12 of the hood, and, if desired, the same fastening means employed to unite the parts of the hood may also engage the corresponding edges of the apron. The cut-out portion 15 terminates in two parallel edges 16, the same being united to the straight sides of the part 11 of the hood when said hood and the apron are united. The upper edge of the apron is reinforced and provided with straps 17, whereby the same may be supported from the top of the vehicle. Extending from this top edge to the apex of the part 12 is a strap 18, the lower end thereof being secured at the point indicated in any preferred manner. At the point of union of the strap 18, the hood 10, and the apron a stay or reinforcing-section 19 is provided to compensate for the wear and strain. Suitable stays 20 are also provided at each end of the hood, one of said stays serving also as a flap to cover an opening 21 for the whip-socket. The rein-holes are each covered by a flap 22, the upper inner corner thereof being cut in the form of an acute angle, whereby the same will divide a stream of water passing down the side of the apron and cause the same to shed away from the said holes.

In practice the hood 10 is placed over the dashboard of a vehicle and the straps 17 secured to the top. When the parts are thus positioned, it will be noted that the central strap 18 will support the apron in such manner that the sides will slope from the center, the peculiar union between the hood and the apron accentuating this relation of the parts.

The advantages of my improved storm-apron will be readily apparent to those skilled in the art. It will be readily observed that by placing the piece 12 on the inside of the hood the latter will be caused to fit snugly

over the dashboard and additional fastenings are dispensed with. A further advantage of this arrangement is that the member 12 holds the seam caused by the union with the apron 5 close to the dashboard, the strap 18 causing the strain to come at the top of the dashboard, thereby allowing the apron to sag below the seam, so that water cannot enter at the latter point. A further advantage is secured by 10 means of the central strap, which serves to maintain the center of the apron at the highest point along its entire length, whereby the water is shed to both sides and in a forward direction. It will also be observed that by providing flaps for the rein-holes and whip-socket, arranged in the manner described, all water 15 is deflected away from those openings.

I claim as my invention—

1. A storm-apron comprising a hood formed 20 of two members united together, and an apron secured at its lower edge to said hood along the line of union of the members of the latter.

2. A storm-apron comprising a hood formed 25 of two members having angular edges united together, and an apron also having an angular portion secured to said hood along the line of union of said angular edges thereof.

3. A storm-apron comprising a hood, an apron secured thereto and having securing- 30 straps, and a central supporting-strap extending from said hood to the top edge of said apron.

4. A storm-apron comprising a hood formed 35 of two members united together, an apron secured at its lower edge to said hood along the line of union of the members of the latter, and a central supporting-strap extending from the top edge of said apron to said hood.

5. A storm-apron comprising a hood formed 40 of two members having angular edges united

together, an apron secured at its lower end to said hood along the line of union of said angular edges, and a central supporting-strap extending from said hood to the top edge of said apron.

45

6. A storm-apron comprising a hood formed of two members having angular edges united together, and an apron also having an angular portion secured to said hood along the line of union of said angular edges, the angular portion of said apron terminating in parallel 50 extensions secured to the end edges of said hood.

7. A storm-apron comprising a hood formed of two members united together, an apron secured at its lower edge to said hood along the line of union of said members, and stays extending over the top edge of said hood.

8. A storm-apron comprising a hood, an apron secured thereto and provided with rein- 60 holes, means for holding said apron elevated along its central line, and flaps fitting over said rein-holes and provided with deflecting corners located adjacent said central line of the apron.

9. A storm-apron comprising a hood formed of two members united together, said hood having an opening therein, an apron secured at its lower edge to said hood along the line of union of said members, and stays fitting 70 over the ends of said hood, one of said stays forming a flap for said opening.

In testimony whereof I have signed this specification in the presence of two subscribing witnesses.

GEORGE A. HUGHES.
